Inventor
George L. Pierce
By his Attorney
Frank D. Hart.

UNITED STATES PATENT OFFICE.

GEORGE L. PIERCE, OF BROOKLYN, NEW YORK.

PLAYING BALL.

Application filed May 10, 1926. Serial No. 108,030.

- This invention aims to provide a simple and efficient structure by which a bladder carrying a valved inflating stem can be secured to the cover. The bladder is attached to a protecting member which is held in place by the lacing used to close the opening in the cover, a small opening being provided in the cover for access to the inflating stem.
- 10 A ball as disclosed herein can be inflated through the inflating stem without opening the lacing, it being necessary to remove the lacing only when it is desired to replace the bladder.
- 15 While I have disclosed a commercial embodiment of the invention for purposes of illustration, it should be understood that various changes in the structure can be made without departing from the spirit and scope 20 of the invention as hereinafter set forth and claimed.
- In the drawings;
- Fig. 1 is a perspective view of a football embodying the invention;
- 25 Fig. 2 is an enlarged detail section on line 2-2 of Fig. 1 showing the relation of the parts during assembling;
- Fig. 3 is a view similar to Fig. 2 showing the parts in assembled relation;
- 30 Fig. 4 is an enlarged detail section on line 4-4 of Fig. 1 with the parts in the position of Fig. 2;
- Fig. 5 is a section on line 5-5 of Fig. 4;
- Fig. 6 is a section on line 6-6 of Fig. 5.
- 35 Referring to the drawings more particularly, the bladder 10 carries a valved inflating stem 11 of a well-known type. A protecting flap of leather 12 of a size to extend beyond the ends of the usual slit 13 in 40 the cover 14 has a metallic bushing 15 attached thereto in any convenient manner. The bushing has an aperture therethrough screw-threaded to receive the threads on the exterior of the inflating stem 11. A smaller 45 leather patch 16 is secured to the upper surface of flap 12 in overlapping relation to bushing 15 and has an opening coinciding with the aperture in the bushing, as clearly shown in Figs. 2 and 4.
- 50 A pair of spaced parallel slits are made through patch 16 on opposite sides of the bushing thereby forming loops 17. A lacing 18 is passed through the lacing holes conventionally arranged on opposite sides of the cover opening 13, and also through the 55 loops 17 each of which is so placed as to lie in the line taken by the lacing in passing between two opposed holes in the cover.
- With the parts loosely positioned as shown in Figs. 2 and 4, the lacing is drawn taut, 60 thereby closing the slit 13 and drawing the flap 12 up against the cover 14 with the stem 11 projecting through an aperture 19 in the cover. The ball is now inflated in a well-known manner, after which a cap 20 65 is screwed into the stem 11, practically filling the aperture 19 as shown in Figs. 1 and 3.
- While I have illustrated the invention as applied to a football it will be evident that it can be used on any playing ball having 70 an inflatable bladder within a cover.
- I claim:
1. In a playing ball, a cover, a slit in said cover, notches in the sides of said slit forming an aperture, a bladder, an inflating stem 75 carried by the bladder and accessible through the aperture, and a lacing closing the slit and holding the bladder against movement relative to the casing.
  2. In a playing ball, a cover, a slit in said cover, a protecting flap, a bladder secured to the flap, and a lacing for closing the slit and holding the flap in position.
  3. In a playing ball, a cover, a slit in said cover, a protecting flap, a bushing secured 85 to said flap, a bladder, an inflating stem carried by the bladder and secured to the bushing, and a lacing for closing the slit and holding the flap against movement relative to the cover.
  4. In a playing ball, a cover, a slit in said cover, a protecting flap, a bushing secured to said flap, a bladder, an inflating stem carried by the bladder and secured to the bushing, and a lacing for closing the slit, said lacing 95 also engaging the flap and holding the flap against movement relative to the cover.
  5. In a playing ball, a cover, a slit in said cover, a protecting flap, a bushing secured to said flap, a patch attached to the 100 flap, loops formed in the patch, a bladder attached to the bushing, and a lacing closing the slit and passing through the loops to anchor the bladder in position.

In testimony whereof I affix my signature.
GEORGE L. PIERCE.
